(57) **CLAIM**

We claim the ornamental design for a compressor, as shown and described.

DESCRIPTION

The design application contains at least one drawing executed in color. Copies of this design application publication with color drawings will be provided by the Office upon request and payment of the necessary fee.

FIG. 1 is a perspective view from the front and right hand side of a compressor in accordance with an embodiment of the present invention;

FIG. 2 is a front view of the compressor shown in FIG. 1; FIG. 3 is a rear view of the compressor shown in FIG. 1; FIG. 4 is a top view of the compressor shown in FIG. 1; FIG. 5 is a bottom view of the compressor shown in FIG. 1; FIG. 6 is a left side view of the compressor shown in FIG. 1;

FIG. 7 is a right side view of the compressor shown in FIG. 1;

FIG. 8 is a perspective view from the front and right hand side of a compressor in accordance with a second embodiment illustrated with shaded color drawings and markings; FIG. 9 is a front view of the compressor shown in FIG. 8; FIG. 10 is a rear view of the compressor shown in FIG. 8; FIG. 11 is a top view of the compressor shown in FIG. 8; FIG. 12 is a bottom view of the compressor shown in FIG. 8;

FIG. 13 is a left side view of the compressor shown in FIG. 8;

FIG. 14 is a right side view of the compressor shown in FIG. 8;

FIGS. 15 is a perspective view from the front and right hand side of a compressor in accordance with a third embodiment of the present invention;

FIG. 16 is a front view of the compressor shown in FIG. 15; FIG. 17 is a rear view of the compressor shown in FIG. 15; FIG. 18 is a top view of the compressor shown in FIG. 15;

(Continued)

FIG. 19 is a bottom view of the compressor shown in FIG. 15;
 FIG. 20 is a left side view of the compressor shown in FIG. 15;
 FIG. 21 is a right side view of the compressor shown in FIG. 15.
 FIG. 22 is a perspective view from the front and right hand side of a compressor in accordance with a third embodiment illustrated with shaded color drawings and markings;
 FIG. 23 is a front view of the compressor shown in FIG. 22;
 FIG. 24 is a rear view of the compressor shown in FIG. 22;
 FIG. 25 is a top view of the compressor shown in FIG. 22;
 FIG. 26 is a bottom view of the compressor shown in FIG. 22;
 FIG. 27 is a left side view of the compressor shown in FIG. 22;
 FIG. 28 is a right side view of the compressor shown in FIG. 22;
 FIG. 29 is a perspective view from the front and right hand side of a compressor in accordance with a fifth embodiment of the present invention;
 FIG. 30 is a front view of the compressor shown in FIG. 29;
 FIG. 31 is a rear view of the compressor shown in FIG. 29;
 FIG. 32 is a top view of the compressor shown in FIG. 29;
 FIG. 33 is a bottom view of the compressor shown in FIG. 29;
 FIG. 34 is a left side view of the compressor shown in FIGS. 29; and,
 FIG. 35 is a right side view of the compressor shown in FIG. 29.
 The broken lines shown in the drawings are for purposes of illustrating the boundaries of the claimed portions as well as unclaimed portions and unclaimed features of the compressor.
